George A. Prevost
Atty.

UNITED STATES PATENT OFFICE.

GEORGE KENELM FIELD, OF LONDON, ENGLAND.

MEANS FOR CONVERTING ROTARY MOTION INTO RECIPROCATING MOTION AND VICE VERSA.

Application filed July 27, 1923. Serial No. 654,215.

To all whom it may concern:

Be it known that I, GEORGE KENELM FIELD, a subject of the King of Great Britain, residing at Ulster Chambers, 168 5 Regent Street, London, England, have invented new and useful Improvements in or Relating to Means for Converting Rotary Motion into Reciprocating Motion and Vice Versa (for which I have filed an application 10 in Great Britain on April 19, 1922, No. 11,051), of which the following is a statement.

This invention relates to mechanism such as that described in the specification of 15 British Letters Patent No. 124,649 wherein the reciprocatory motion of members, for instance, pistons, plungers and the like, is the resultant of rotatable motion of a shaft or like device and vice versa, and is particularly applicable to air, liquid and gas 20 pumps, compressors, ported sleeves and the like, and can be employed for steam and internal combustion engines, or, any other form of mechanism employing two or more reciprocating members operating a single 25 rotatable member and vice versa.

In the said former specification there is described a single member designed to be simultaneously reciprocated and oscillated 30 around an axis extending in the direction of reciprocation by a single rotatable member through the medium of a crank-pin or eccentric member slidably longitudinally with respect to the crank or rotatable member 35 carrying it.

According to this invention a plurality of co-planar members are each reciprocated and simultaneously oscillated around an axis extending in the direction of reciprocation 40 and which axes may intersect one another, by means of a single rotatable member through the medium of a single crank-pin or eccentric member and/or vice versa in such a manner that, although the various 45 reciprocating members may not reciprocate synchronously, or in the same plane with each other, the oscillatory movement of each is in direct relationship to its reciprocating movement and can consequently be utilized 50 for controlling inlet and discharge ports or the like, or the rotatable member may be the driven member.

In a suitable arrangement for carrying 55 this invention into effect the crank-pin or eccentric member is pivoted or otherwise

conveniently connected to one or more or all of the reciprocating members, in which case the part thereof in engagement with the rotatable member will be free to revolve therein or thereupon and, at the same 60 time, free to move axially in relation thereto.

The reciprocating members are of a shape or form to permit of the oscillatory turning movement and each may be of double purpose or double acting. 65

The duty end or ends of a reciprocating member remote from or on either side of the line or point of contact or connection of the eccentric member may be flat, cupped or of any other suitable shape, and ports 70 may be provided in the side or wall thereof when required for the purposes of suction and discharge.

Each reciprocating member will be supported in a guide or casing or the like of 75 suitable form and dimensions to permit of the correct functioning of the reciprocating and oscillatory turning movement and, suitably and conveniently attached thereto will be the housing containing the rotatable 80 member.

My invention is also applicable to rotary engines or pumps and the like, in which case the reciprocating members, together with their casings, will be revolved within 85 another fixed casing to which will be rigidly attached the crank shaft heretofore referred to as the rotatable member.

To enable the invention to be fully understood I will describe it by reference to the 90 accompanying drawing, in which:

Figure 1 is a sectional side view of a reciprocating pump constructed in accordance with the invention and embodying two cylinders each having a double acting 95 plunger.

Figure 2 is a sectional plan view of the pump.

Figures 3 and 4 are, respectively, sections on the lines 3-3 and 4-4, Figure 1. 100

a, b are the two pump cylinders which are arranged in the same plane and intersect each other at right-angles and *c, d* are the double acting plungers designed to be reciprocated and also oscillated within the 105 respective cylinders *a, b*. *e* is the shaft for effecting the reciprocation of the plungers through the medium of the crank-pin *f* which is pivoted to both plungers *c, d* by the pivot pins *g, h* respectively, the said 110

pins being eccentrically arranged with respect to the said plungers, so that the rotation of the shaft *e* will, in addition to reciprocating the plungers, also cause the oscillation thereof, the crank-pin *f* sliding longitudinally in a corresponding hole *i* in the said shaft to allow of such oscillation. The peripheries of the plungers *c*, *d* are extended at the ends in cup form as indicated at *c*¹, *c*¹, *d*¹, *d*¹, respectively, the said extensions being provided with ports *j*, *k* which co-act respectively with ports *l*, *m* in the cylinders for the purpose of suction and discharge of the fluid being pumped. *n*, *o* are the suction and discharge orifices of the pump, which orifices open, respectively, into chambers *p*, *q*. The ports *l*, *m* open, respectively, into the said chambers *p*, *q*.

The shaft is shown as being driven by a crank-handle *r* through the medium of spur-wheels *s*, *t*, but it may be driven by power.

In Figures 3 and 4 I have indicated the exact relationship of the ports *j*, *k*, *l*, *m* of the cylinder *a* and piston *c*; it will, however, be understood that the corresponding ports of the cylinder *b* and piston *d* will be similarly arranged.

Although I have described a pump in which a pair of co-planar cylinders containing a pair of plungers are designed to be reciprocated and oscillated by a rotary shaft through the medium of a crank-pin or eccentric longitudinally slidable member, it is to be understood that more than two such co-planar cylinders may be employed and that parallel with such co-planar cylinders may be arranged another similar set of cylinders and plungers operable by the same

crank-pin or eccentric member or by another such member at the other end of the shaft.

It is also to be understood that, although I have described my invention in connection with a pump, my said invention is not restricted to such use but may be employed for steam and internal combustion engines, or in other instances where it is required to impart both a reciprocating and an oscillating movement. Furthermore, the mechanism can be employed for converting the reciprocating and oscillating movements of two or more reciprocating members into a movement of rotation.

Claims:

1. Mechanism of the type hereinbefore referred to, including a plurality of co-planar members, members eccentrically secured to said co-planar members for reciprocating and simultaneously oscillating said co-planar members through and about intersecting axes, and a crank pin through which said members pass.

2. Mechanism of the type hereinbefore referred to, including a plurality of cylinders arranged in the same plane and intersecting each other at right angles, a plurality of double acting plungers adapted to be reciprocated and simultaneously oscillated within said respective cylinders, through intersecting axes, a shaft for reciprocating said plungers, having a crank pin and pivot pins eccentrically mounted in said plungers, and passing through said crank pin.

GEORGE KENELM FIELD.
